UNITED STATES PATENT OFFICE

WILLIAM J. GANNET, OF CLEVELAND, OHIO.

INTERNAL-COMBUSTION ENGINE.

Application filed May 25, 1922. Serial No. 563,641.

My invention relates to improvements in internal combustion engines and more particularly to the two-cycle type of engine wherein the gas mixture is compressed and ignited at each compression stroke of the piston while the spent gases are discharged and additional gas mixture is supplied to the cylinder during and at the conclusion of the outward stroke of the piston.

The prime objects of my invention are to insure better control of this type of engine than has previously been effected, better action of the double-functioned piston and greater certainty of operation during conditions of extreme throttling of the gas mixture. Other objects and advantages will appear in connection with the accompanying description of the preferred embodiment of said invention.

The two-cycle engine herein shown and described preferably is built in two-cylinder units or multiples thereof, but a simple two-cylinder engine will suffice for explaining the features of my improvement herein claimed. This engine is provided with a normally open exhaust port which is controlled solely by the position of the piston and with an inlet port for the gas mixture which is controlled primarily by a link-motion connected with the piston and secondarily by a throttling lever for regulating the position of the valve member. This valve member is of a specialized rocking type which cooperates with a suitable cylinder port or ports and a receiving pocket or pockets upon the piston head for holding a limited or proportionate quantity of the gas mixture out of contact with the spent gases, in which pocket the charge is fired by the adjacent or entrant spark plug at the completion of each compression stroke. The structural details and their functions may be more readily explained by making reference to the accompanying drawings, wherein:

Figure 1 is a view of the preferred two-cycle combustion engine in vertical section showing the relation of the parts at the conclusion of the out-stroke.

Fig. 2 is a similar view illustrating the positions of the respective parts at the mid-stroke of the piston.

Fig. 3 is also a vertical section showing the members in their relation at the completion of the compression stroke.

Fig. 4 is a transverse section through the

engine, the position, however, being reversed, and

Fig. 5 is a fragmentary vertical section, illustrating the chamfered valve and its port.

Throughout the several figures of the drawings I have employed the same character of reference to indicate similar parts.

It will be unnecessary to explain all of the details of construction shown in the drawings, since certain features of the internal combustion engine therein illustrated are common to all engines of this general class, hence I shall principally confine my description to the features of improvement defined in the appended claims. These improvements correct the common disadvantage inherent in two-cycle engines because of the inability to control their operation accurately in accordance with the torque or load. This I have accomplished by employing suitable valve mechanism for controlling the gas mixture independently of the piston and properly timing its admission to the explosion chamber. This control also prevents leakage of the gas mixture past or around the piston from the inlet port to the exhaust port as will be further explained.

Referring first to Figure 1 of the drawings, the usual water-jacketed cylinder *a* is shown with the piston *b* at the completion of its out-stroke and with the rocking valve *c* open to clear the inlet port *d* positioned laterally of said cylinder *a*. The exhaust port *e* and inlet port *d* are cleared by the piston so the bulk of the spent gases have been discharged and the charge of gas mixture has entered the pockets *f* and has assisted in expelling the spent gases from the upper portion or explosion chamber of cylinder *a*.

Figure 2 illustrates the relation of the parts with the piston advanced substantially one-half of its compression stroke into the explosion chamber, thus closing the inlet and exhaust ports, while the valve *c* has immediately been rocked into position to close the inlet port and partially close the by-pass chamber *g*. The upward stroke of the piston has partly completed the compression of the gas mixture in explosion chamber *a'*, while the next charge of gas mixture has been partially drawn into the annular chamber *a''* within and under the piston *b* from the associated carburetor (not shown in the drawings).

The rocking valve is actuated by a link-motion comprising the bent connecting rod *h* which is pivoted to the short arm of bell crank lever *i* fulcrumed on the pivoted adjusting arm *j*, while the long arm of said bell crank lever *i* is pivoted at the outer end of link *k*, and this, in turn, is pivoted at its inner end upon the cross-head *l* of the piston. Accordingly, the effective position of valve *e* may be adjusted by altering the fulcrum of the link-motion through the pivoted adjusting arm *j*, as indicated by dotted lines in Fig. 3.

Figure 5 shows the chamfered or cut-away valve face *c'*, variable portions of which may be rocked past the port to afford greater or less clearance and approximately register with all of the compartments or merely the central one of the charge pockets *f* provided upon the piston. This adjustment is accomplished by the described movement of the link-motion within the range of its adjusting arm, whereby the admission of the gas mixture may be accurately regulated.

It will be observed that the gas pockets *f* are provided with a contracted or inturned rim, so that the tendency is to retain the fresh mixture within the pocket or pockets initially charged. When the valve *e* is adjusted to permit the gas mixture to flow only through the apex of its chamfered face, said mixture will be confined to the central pocket *f* as far as possible and maintained out of contact with the spent gases remaining in chamber *a'*. Consequently, the adjacent or entrant spark plug *l*, which is positioned at one side of the cylinder head, will ignite the undiluted gas in said pocket and avoid missing under conditions of close throttling.

The relative positions of the several parts of the engine at the moment of ignition are well shown in Fig. 3, from which it will be observed that the spark plug terminals are adjacent to the rim of the central charge-pocket *f* containing the compressed gas mixture and by which the charge invariably will be ignited. The valve *e* is shown in position completely closing the by-pass and thereby cutting off the lateral gas inlet *d* during the out-stroke now performed by the piston. This means that the primary compression of the gas mixture within the annular chamber *a''* and the by-pass *g* is held by said valve *e*, thereby preventing leakage around the piston from the inlet port to the exhaust port. This is of marked importance in the operation of a two-cycle engine and avoids the side-thrust that otherwise would affect the piston if the gas pressure were applied laterally thereto.

The link-motion shown and described per-

mits the closure of the valve *e* during substantially the entire outstroke of the piston, while effecting a rapid opening of the valve *e* at its conclusion.

Having now described the preferred embodiment of my invention, I claim as new and desire to secure by Letters Patent, together with such modifications as may be made by the expected skill in this art, the following:

1. In an internal combustion engine of the class described, the combination with the engine cylinder having an inlet port positioned laterally thereof, of a reciprocating piston having a plurality of charge-pocket compartments traveling in said cylinder and adapted to clear the port at the extremity of its out-stroke, an oscillating valve member normally closing said port and angularly cut away to afford a variable clearance therewith, and automatic means connected with said piston for variably opening said valve, substantially as set forth. 85

2. In an internal combustion engine, the combination with the engine cylinder having an inlet port positioned laterally thereof, of a valve member controlling said port, means for varying the effective clearance of said valve member, a piston reciprocating in the cylinder, and a charge-pocket having a plurality of laterally closed compartments provided upon said piston adapted to be brought into register with the port to receive and hold variable charges of gas mixture, substantially as set forth. 95

3. In an internal combustion engine, the combination with the engine cylinder having a lateral inlet port, of a piston reciprocating in said cylinder, and a laterally closed charge-pocket provided upon said piston having a contracted rim and adapted to be brought into register with said inlet port, substantially as set forth. 100

4. In an internal combustion engine of the class described, the combination with the engine cylinder having a lateral inlet port for the gas mixture, of a valve-member controlling the port; said valve-member being provided with a variable clearance with respect to said port, means for adjusting the effective position of the valve member, a reciprocating piston within the cylinder, a charge-pocket upon the piston having a plurality of compartments adapted to be brought into register with the variable clearance of the valve-member, and automatically actuated mechanism for operating said valve, substantially as set forth. 110

In testimony whereof I do now affix my signature.

WILLIAM J. GANNET.
